UNITED STATES PATENT OFFICE

SIMON LAKE, OF MILFORD, CONNECTICUT

SUBMARINE ELEVATOR OR ESCAPE BUOY

Application filed July 5, 1929. Serial No. 376,220.

This invention relates to a submarine elevator or escape buoy, that is to say, a device whereby ascent from and descent to a submerged or sunken vessel may be accomplished without risk of life and without discomfort.

The apparatus of this invention is in the nature of an improvement on the device of a somewhat similar nature which forms a part of the invention disclosed by my patent for combined surface and submarine vessel, No. 650,758, granted May 29, 1900.

One object of the invention is to so construct the elevator cage or buoy, and the cavity or recess provided in the vessel therefore, of such conformation that, when the buoy has ascended and is returned to the vessel, the cooperation of the respective parts will be such as to insure the proper seating of the buoy within its cavity in such relation to the deck of the vessel that a desired air and water-tight seal may be caused to function between these parts when required.

Another object of the invention is to provide the cage or buoy with such chambers or compartments and communicating covered hatches that safe passage may be had between the cage or buoy and the vessel with which it is associated.

A further object is to provide in apparatus of this kind, a water-ballast compartment and means for supplying air under pressure and water to such compartment, whereby the buoyancy of the apparatus may be so regulated as to control its ascent and descent.

With these objects in view, the invention consists in the combination with a submersible vessel, for example a submarine boat, of a submarine elevator or escape buoy, comprising, inter alia, a casing of substantially conical form adapted to seat within a cavity or recess of similar form in the deck or superstructure of the submersible vessel, means including preferably tubular cables connected with the buoy and vessel being provided for controlling the ascent and descent of the buoy, and the casing being divided by appropriate partition members into a plurality of compartments or chambers including a working chamber in which persons

may be safely confined during ascent and (or) descent of the buoy, a passageway affording communication through suitable hatches between such chamber and the vessel, and means for sealing such passageway when in position for such communication against the entrance of water, and a ballast compartment, all as I will proceed now more particularly to explain and finally claim.

In the accompanying drawings illustrating the invention, in the several figures of which like parts are similarly designated, Figure 1 is a fragmentary plan view of the superstructure of a submersible vessel with the device of my invention applied thereto, a part of the device being broken away to disclose a portion of its interior. Fig. 2 is a sectional elevation taken substantially on line 2-2 of Fig. 1.

The elevator cage or buoy proper has a casing 1 preferably having the conformation of the frustum of a cone. This buoy fits relatively snugly within a similarly shaped cavity or recess 2 built in the superstructure 3 of the submersible vessel 4 and extending to the deck 5 of the main pressure resisting hull thereof.

The casing 1 is interiorly divided by suitable partition members, including a preferably cylindrical member 6, into a working chamber 7, a passageway 8 and a ballast compartment 9. The partition member 10, which forms the deck of the working chamber 7, is provided with a hatch 11 having a hatch-cover 12 which affords communication between the chamber 7 and passageway 8.

The cylindrical member 6 is of such diameter as to receive the hatch 13 of the vessel, including its cover 14 within it, and the bottom or small end of the buoy is provided with a suction cup device similar to that disclosed in my copending application for patent for submarine diving bell and rescue apparatus, filed July 5, 1929, Serial No. 376,221 and operable in substantially the same manner. This suction cup device comprises an annular channel member 15 provided on the outer faces of its flanges with annular lip pieces 16, preferably of soft rubber, these lip

- pieces adapted to bear against the portion of deck 5 surrounding hatch 13 in such manner that when the annular space defined by them is evacuated by means of a pump 17, 5 an air and water-tight connection is provided between the buoy and the deck 5, the passageway 8 is effectively sealed and the buoy is attached to the vessel within the cavity 2 with a suction grip of great tenacity. 10 When it is desired to free the buoy this grip may be broken by opening a valve 18 and permitting water to enter the suction device. With the buoy seated and sealed, as described, the hatches 11 and 13 afford a means 15 of safe communication between the hull of the submersible vessel and the cage or buoy. In order that the cage or buoy may be guided and controlled during its ascent and descent, I provide a plurality (two being 20 shown) of cables 19 and 20 wound upon drums 21, 22 and 23, 24, respectively. The drums 21 and 23 are arranged in suitable sealed chambers 25 in the buoy, and the drums 22 and 24 are arranged in similar 25 chambers 26 in the vessel. As shown, the cables 19 and 20 are preferably tubular and are in communicating connection with the interiors of their respective drums which are also tubular. By these means air may be fed 30 from suitable storage in the vessel to the chamber 7 through a pipe 27 and by way of drum 22 and tubular cable 19 to drum 21, and thence through a pipe 28, its escape from which may be controlled by a valve 29. Air 35 under pressure may be fed also through a pipe 30, drum 24, tubular cable 20, drum 23 and a pipe 31 to the passageway 8 and ballast compartment 9 by way of valve-controlled pipes 32 and 33, respectively. 40 Each of the drums 21, 22, 23 and 24 is provided with suitable gearing 34 and hand cranks, as shown, or other operating means, either manually or power operated, whereby the paying-out and hauling-in of the cables 45 and the ascent and descent of the buoy may be suitably controlled. The ballast compartment may be fed with and exhausted of water by way of a valve-controlled pipe 35. 50 The casing 1 is provided with a preferably domed head 36 having a hatch 37 and hatch-cover 38 by means of which latter men may enter and leave the working chamber 7 from above. Also the head 36 is provided with a 55 periscope 39 through which observations may be made when the buoy is near the surface. Hinged dogs 40 provided with threaded operating rods 41 extending into the hull of the vessel and operated by means of hand wheels 42, furnish a means whereby the buoy 60 may be mechanically locked within its cavity 2, and by which it may be released. It will be understood that all of the hatch-covers will be provided with operating means

whereby they may be opened and closed either from within or from without. Such means being well known, they have not been illustrated in the drawings.

Assuming that the elevator cage or buoy 70 is locked in its cavity or recess 2, as shown in Fig. 2, and that a suction grip is maintained by the device 15-16, an ascent to the surface may be made in the following manner:—The members of the crew who wish 75 to ascend enter chamber 7 through hatch 13, passageway 8 and hatch 11, and close the hatch-covers 14 and 12 behind them. Then they signal for the dogs 40 to be released, and after that has been done they admit water to 80 the suction device 15-16 by opening valve 18, thus breaking the suction grip and freeing the buoy. Air pressure is then admitted to passageway 8 by way of pipes 31 and 32. If the buoy does not rise, water is blown 85 from the ballast compartment 9, through pipe 35, by admitting air to the compartment through pipe 33. Buoyancy of the buoy having thus been increased, it will float upward, its ascent being controlled and regulated by 90 means of the cables 19 and 20 either from within the buoy by operation of the drums 21 and 23, or from within the vessel by operation of the drums 22 and 24. Arrived at the surface, the men may open hatch 37 and 95 leave the buoy.

To descend again to the submarine vessel it is only necessary to close hatch 37, flood the ballast compartment 9 and haul in on the cables 19 and 20. As the buoy descends a 100 constant supply of air is furnished to the passageway 8 to prevent the water from exerting too great a pressure upon and leaking past hatch-cover 12. In this returning of the buoy to the submarine vessel the function 105 of its frusto-conical shape will become apparent. If an under-water current should carry the buoy away from the vessel, the hauling-in of the cables will gradually draw the buoy toward the cavity 2 and it will not hang on the deck of the superstructure but will eventually center itself to its seat in the cavity.

This complementary conical conformation of the buoy and cavity is also of advantage 115 in freeing the buoy. There is no friction between the buoy and the walls of its cavity for the reason that as the buoy ascends the space between the buoy and the walls of its cavity increases and permits the water to 120 rapidly replace the bulk of the buoy.

An adequate supply of air under pressure may be carried in tanks in either the buoy or submarine vessel, or both, or it may be supplied from a surface vessel.

It will be seen that I provide apparatus by means of which the crew of a sunken submarine may be saved without aid from others, except that they be picked up from the buoy when it is at the surface. Also, I 130

provide apparatus whereby the crew of a submarine boat resting upon the bottom may rise to and descend from the surface at will to take observations, obtain munitions and supplies and do other necessary things, without risk of life or detection, and without discomfort.

Various changes are contemplated as within the spirit of the invention and the scope 10 of the following claims.

What I claim is:—

1. A submarine elevator or escape buoy in combination with a submersible vessel, said buoy comprising a casing of inverted frusto-conical form, a cavity in said vessel of complementary form, means within said casing defining a working chamber and a passageway communicating therewith and a ballast compartment, said passageway extending through the lower end of said buoy and means surrounding the lower end of said passageway for connecting said buoy air and water-tight to said vessel, said connecting means being properly seated by cooperation 20 of the complementary frusto-conical surfaces of the buoy and cavity.

2. A submarine elevator or escape buoy in combination with a submersible vessel, said buoy comprising a casing of inverted frusto-conical form, a complementally formed cavity in said vessel, partition members within said casing defining a working chamber and a passageway and a ballast compartment, a hatch in the partition member between said 30 working chamber and passageway, a hatch in the deck of said vessel within said cavity, said hatches and passageway affording communication between said vessel and working chamber, and means carried by said buoy and surrounding the lower end of said passageway and adapted for cooperation with said deck whereby said buoy may be connected to said vessel and said passageway sealed air and water-tight when said hatches 40 are open, the complementary conformation of said buoy and cavity providing guiding means whereby the sealing means may properly engage said deck.

3. A submarine elevator or escape buoy in combination with a submersible vessel, comprising a casing provided with a working chamber and a ballast compartment, means for admitting water to and exhausting water from said ballast compartment, and means 50 including a tubular cable connected with said buoy and vessel for supplying air under pressure to said ballast compartment and for controlling the ascent and descent of said buoy.

60 In testimony whereof I have hereunto set my hand this third day of July, A. D. 1929.

SIMON LAKE.
